(57) CLAIM

The ornamental design for a party pick as shown and described.

DESCRIPTION

FIG. 1 is a top perspective view of the party pick showing my new design.

FIG. 2 is a top view thereof;

FIG. 3 is a right side view thereof;

FIG. 4 is bottom view thereof;

FIG. 5 is a left side view thereof;

FIG. 6 is a rear view thereof; and,

FIG. 7 is a front view thereof.

The broken lines in the drawings depict structure and form no part of the claimed design, and the broken lines immediately adjacent to the shaded areas depict the bounds of the claimed design, while all other broken lines are directed to environment.

1 Claim, 7 Drawing Sheets
